HEATING SYSTEM

Warren T. Ferguson, Waban, and Joseph A. Parks, Jr., Milton, Mass., assignors, by mesne assignments, to Anderson Products, Incorporated, a corporation of Massachusetts

Application July 30, 1935, Serial No. 33,838

10 Claims. (Cl. 237—9)

This invention relates to one-pipe steam heating systems, particularly those one-pipe systems which operate in cycles under the control of a thermostat. One of the objects of this invention is to provide means for controlling the distribution of steam to the radiators on each cycle of operation and to provide additional means for insuring the operation of the steam distribution controlling mechanism.

10 One of the faults present in the so-called vacuum heating system is the refusal of the steam to distribute itself properly under certain conditions and during certain heating cycles. If, for example, by condensation of the steam, the negative pressure in the system has reached a point where the water will boil at a low temperature, say 190 degrees, the inauguration of the next cycle by the operation of the thermostat under the influence of falling room or outside temperature will promptly cause the generation of correspondingly low temperature steam. The advent of this steam however will not dissipate the negative pressure until a substantial amount of steam has been created. As a result the system remains sealed, the vacuum valves continuing closed, and steam drifts about aimlessly, sometimes proceeding to certain radiators, sometimes to others, depending to some extent on external weather conditions. In other words, when steam is formed while a negative pressure exists, control of distribution is impossible.

One of the objects of our invention is therefore to bring the pressure in the system back to atmospheric at the start of each cycle, so that the steam distribution can be definitely controlled by our adjustable venting valves following their resetting to venting position upon the dissipation of the negative pressure in the system.

40 A further object of our invention is to provide an improved method of distributing steam in a one-pipe steam heating system.

Other objects and accomplishments of this invention will more clearly appear hereinafter as the details of our invention are more particularly set forth.

In the drawing,

Fig. 1 is a schematic showing of the system.

Fig. 2 is a cross-section of a suitable vacuum-breaking relief valve for use in our system.

50 Fig. 3 is a cross-section of an adjustable air-venting vacuum maintaining valve suitable for use in our system.

Our system is distinguished by two features. First, we provide means on the radiators themselves for controlling the distribution of steam

to the radiators, and secondly, we provide other means for insuring the operation of the first means on each cycle of operation of the system.

The means that we use for controlling the distribution of steam to the radiators is a venting valve as shown in Fig. 3, although it is pointed out that any other type of adjustable venting valve capable of maintaining a closed position under negative pressures in the system could be used equally well.

10 The means that we use to insure the radiator venting valves performing their function on each cycle of operation is a relief or vacuum-breaking valve that will be more fully described hereinafter.

15 Referring now more particularly to the drawing; in Fig. 1 is shown a schematic arrangement of a one pipe steam heating system employing our invention. There is a boiler 2, having a source of heat 4, as for example, an oil burner 20 or a gas burner capable of remote control by a thermostat 6. Leading from the boiler 2 is a steam main 8 from which the pipes, or risers 10, 12 and 14, extend upwardly to the radiators R1, 20 R2, and R3 positioned in various parts of the 25 structure to be heated.

On each radiator is an adjustable air venting valve as V1, V2, and V3, shown in detail in Fig. 3, and to be more fully described hereinafter. These valves, capable of adjustment to vary their venting capacity, are for the purpose of permitting the air to escape at pre-determined rates from the radiators.

30 Positioned on steam main 8, usually at a point remote from the boiler 2, is the negative pressure or vacuum relief valve 16 shown in detail in Fig. 2. Thermostat 6, of usual construction, is positioned in some part of the building to be heated, usually in a location where it may be influenced by the radiators R1, R2, and R3. The wires 20 and 22 40 lead to the relay 24, which, when actuated by the closing of thermostat 6, closes the circuit 26, 28, which starts the fire in boiler 2 and also closes the parallel circuit 30, 32, leading to the relief valve 16.

45 Fig. 2 shows the essential features of our vacuum relief valve 16. 34 is a threaded nipple which is screwed into a tapped hole in the steam main 8. Casing 36, mounted on nipple 34, has positioned thereabove a solenoid 38 which provides the means to operate valve 40. It will be noted that the casing 36 is divided into two portions, a right-hand portion through which air and steam can pass, and a left-hand portion separated therefrom

by a partition 42, and containing a switch 44, and bellows controlled operating means therefor.

Within the right-hand portion is a float 46 which prevents the escape of water from the valve 16 should the system inadvertently become filled, the float 46 rising and closing passageway 48.

Lead wire 30 is connected with one terminal of the solenoid 38. Lead wire 32 is connected with one terminal of switch 44. From the other terminal of switch 44 to the other terminal of solenoid 38 is the conductor 54. Switch 44 is normally closed so that the circuit through conductors 30, 54, and 32 is continuous.

Part of the partition 42, dividing casing 36, 15 consists of a thermostatic unit 56 having a casing 58 which houses bellows 60. The bellows is sealed to the casing at 62 so that the space therebetween is air-tight. Within this sealed portion is preferably a small amount of a volatile liquid such as 20 alcohol. Extending axially from the head of the bellows is a compression member 64, engaging lever 66 of switch 44. A small movement of compression member 64 to the left by collapse of bellows 60 operates lever 66 to open switch 44.

25 With solenoid 38 inoperative, valve 40 and its associated valve stem 68 are urged upwardly by spring 70, forcing valve 40 against valve seat 72, closing passage 74. Operation of the solenoid 38 drives the valve stem 68, and valve 40, downwardly, permitting the passage of air through port 76, passage 74, chamber 78, passage 48, and into the steam main 8 through the nipple 34.

Fig. 3 shows a radiator air venting valve suitable for use on the radiators in our system. The 35 valves, V1, V2, and V3, shown in Fig. 1 may be of this construction. The valve shown in Fig. 3 comprises a base 80, to which is secured a casing 82 by means of the lock nut 84. A nipple 86, which may be threaded into a tapped hole in the 40 radiator, extends from the base, and loosely positioned therein is a siphon tube 88 which assists in returning the condensate to the radiator. Positioned in the top of the shell 82 is a venting member 90, having a passageway 92 therethrough, 45 and a valve seat 94. Mounted within the sealed base and shell is a bellows 96 and a thermostatic float 98, the float having a valve pin 100 mounted adjacent the vent. Both the bellows and float are adjustably mounted on the base by means of 50 the stem 102, which by virtue of threaded engagement with the base 80 may be rotated to move both the bellows 96 and float 98 vertically.

The supporting means for stem 102 comprises a sleeve 104 threaded internally and externally 55 as shown. This sleeve is screwed into a suitably threaded hole in the base, as at 106, and threaded within the sleeve is the stem 102. Positioned on the upper end of sleeve 104 is a stop 108 in the form of a split washer secured in place by a cap 60 110. A groove 112 is formed in the stem 102, the stop 108 being positioned therein. It is clear from this construction that the upward and downward movement of the stem 102 with relation to sleeve 104 is definitely limited by the width of groove 112 65 and the thickness of stop 108. Suitable packing means 114 and 116 is provided at the lower part of stem 102 to prevent the escape of steam or water.

The bellows 96, closed at its upper end, is 70 mounted on a base 118 which in turn is mounted on the stem 102, the upper end of the stem being of such length that it just grazes the end of the bellows at 120 when the latter is in normal position. The purpose of this stem extension 75 is to prevent collapse of the bellows beyond its

normal length, which if permitted would change the venting rate of the valve. An air passage 122 extends through the stem 102 allowing the atmosphere to reach the interior of the bellows 96.

Supported by the stem and bellows is the float 5 98 which is sealed, and usually has a small quantity of a volatile liquid contained therein. The bottom 124 of the float is normally concave as shown, but when the temperature of the float is raised by the presence of steam, the bottom 124 is 10 caused to snap downwardly to a convex position due to the expansion of the fluids within the float. This elongation of float 98 causes valve pin 100 to engage the valve seat 94, thereby closing the valve. 15

The purpose and method of adjustment of stop 108 is as follows. With the stem 102 screwed upwardly as far as possible with relation to sleeve 104, that is, until the lower edge of groove 112 engages the under side of stop 108, and with 20 the float 98 in contracted position, sleeve 104 is rotated with relation to base 80 until the valve pin 100 seats on the valve seat 94. Sleeve 104 is then anchored so that no further rotation between it and base 80 is possible. Stem 102 is 25 then screwed downwardly within sleeve 104 until the upper edge of groove 112 encounters the upper side of stop 108. In this position the valve is wide open and at full venting capacity. However, the travel of stem 102 with relation to 30 sleeve 104 is made less than the downward travel of the bottom 124 of the float 98, as the bottom moves from concave to convex position. Thus it is assured that when the float 98 operates under the influence of heat the orifice 92 will always 35 be closed by the positioning of valve stem 100 against the valve seat 94. Limiting the upward movement of stem 102 so that valve pin 100 can move no farther than is necessary to close the valve by contact with seat 94, eliminates the possibility of damage to the various parts by careless adjustment. By adjusting the position of stem 102, which in turn varies the area of the opening between the end of valve pin 100 and the seat 94, the rate of escape of air from the radiator 45 through the valve may be controlled. The valve will close however under any setting when the steam reaches the float 98. 40

The operation of our system is as follows. When the temperature at the thermostat 6 has 50 fallen to a pre-determined point, the cycle starts as the thermostat operates to close the circuit 20, 22, actuating the relay 24, thereby closing the circuit 26, 28 to the boiler 2, and the circuit 30, 32 to valve 16. Closing the circuit to the 55 boiler starts a fire therein, this being accomplished by any of the several well-known means. Closing circuit 30, 32, results in the operation of solenoid 38 to drive valve stem 68 and valve 40 downwardly, thereby permitting air to enter the 60 system. In this way the pressure in the system is brought to atmospheric, at, or shortly after, the time the fire is started in the boiler. The atmospheric pressure in the system of course extends to the radiators R1, R2 and R3, and the 65 venting valves V1, V2 and V3 attached thereto. Under these conditions, and in the absence of heat, the venting valves will be in normal open position.

Thereafter, steam is generated in the boiler 2 70 and advances along the steam main 8 to the risers 10, 12, and 14, and the relief valve 16, which is usually positioned on the steam main at a point remote from the boiler. Under the influence of the advancing steam, the air in the system will 75

be driven out through the relief valve 16 and the venting valves V1, V2, and V3. Since the venting capacity of relief valve 16 is very much greater than that of the venting valves on the radiators, steam will fill the main 8 relatively quickly. When steam reaches valve 16 it comes in contact with the thermostatic unit 56. As the steam engages the casing 58, the fluid within the thermostatic unit 56 expands, compressing the bellows 60 and driving the compression member 64, which is mounted on the movable head of bellows 60, to the left, thereby operating switch 44 to break the circuit through conductors 32 and 54. This renders the solenoid 38 inoperative, and valve 40, under the influence of spring 10, closes, thereby preventing the escape of steam.

Breaking the circuit through conductors 32 and 54, however, does not break the circuit that controls the operation of the fire in the boiler, since the two circuits are arranged in parallel, or in separate circuits, if desired. Thus the boiler continues to generate steam to be supplied to the radiators in accordance with the venting rates of the valves V1, V2, and V3 which have been adjusted to give the desired distribution. That is to say, by varying the setting of valve pin 100 with relation to valve seat 94, by rotation of the stem 102, the rate of escape of air from the radiators can be controlled. In this way the time of arrival of steam to the several radiators can be adjusted as desired. Thus, the amount of heat distributed to the various parts of the space to be heated, prior to cutting off the steam supply at the end of the cycle, is under full control.

When the steam reaches the valves V1, V2, and V3, the fluid within the thermostatic float 98 expands to drive the bottom 124 downwardly to a convex position, thereby forcing valve pin 100 against valve seat 94 to close the vent 92, preventing further escape of the steam. When the temperature of the building has been raised to a predetermined point, thermostat 6 operates to break the circuit 20, 22, thereby breaking the circuit 26, 28 to the boiler 2 to shut off the fire under the boiler.

With the elimination of the supply of steam, the radiators begin to cool, resulting in condensation of the steam in the system, whereby a negative pressure is developed. When the falling temperature reaches a certain point, the pressure within the thermostatic float 98 will be sufficiently reduced to permit bottom 124 to resume its original concave position. Ordinarily, this would result in the re-opening of the vent 92. However, by means of our bellows 96, which at once expands, due to the fact that the atmospheric pressure within the bellows exceeds the negative pressure within the valve casing, developed by the collapse of the steam, valve pin 100 continues to be held against valve seat 94, thereby maintaining vent 92 in a closed position.

From the construction of venting valves V1, V2, and V3 it is clear that they will remain closed as long as a negative pressure exists in the system, and the only way they may be re-opened to the normal venting position is by bringing the pressure within the system up to atmospheric.

When the temperature at the thermostat has dropped sufficiently, due to the cooling of the structure, the circuit 20, 22 will again be closed to start the next cycle, operating the relay 24 to close the circuit 26, 28 to the boiler, to rekindle the fire therein and to close the circuit 30, 54 and 32 to the relief valve 16 which results in

the opening of valve 40 through the operation of solenoid 38. It should be pointed out here that switch 44, which had previously been opened through the operation of thermostatic unit 56, closes when the thermostatic unit 56 responds to a decrease in temperature resulting from the dissipation of heat.

The opening of valve 40 of relief valve 16, permits the pressure within the system to return to atmospheric, causing the collapse of bellows 10 96 in the venting valves V1, V2 and V3, and the re-opening of vents 92. In this way, all of the venting valves V1, V2 and V3 are reset to normal venting position, whereby the correct distribution of steam may be had on the coming 15 cycle, which is thereafter repeated.

In the event that the thermostat 6 is actuated to shut off the supply of steam by only partially filling the radiators R1, R2, and R3 with steam before the thermostatic floats 98 have operated to close the venting valve V1, V2 and V3 it will make no difference in the effectiveness of our system for the following reason. As has been previously pointed out, the bellows 96 expands to close passage 92 if the pressure within the 25 valve casing is less than atmospheric. Even though the radiators may be only partially filled with steam, when the steam generation stops, the resulting condensation takes place so rapidly that a negative pressure develops within the 30 system even though some air is going back into the radiators through the open ports 92. The pressure differential that is created is sufficient to cause bellows 96 to elongate to close ports 92 to thereby completely seal the system and to put 35 the system in the same condition it would have been in had steam reached the thermostatic floats 98 to close the ports 92 prior to actuation of thermostat 6.

It should be pointed out that the mode of operation may be modified somewhat by varying the strength of the spring 10 in the relief valve 16 to permit valve 40 to open automatically when the negative pressure in the system exceeds any predetermined point. In this way the negative 45 pressure can be definitely limited if it is so desired. By controlling the maximum negative pressure, the time between heating cycles can be controlled to a certain extent.

As previously indicated, we believe we are the first to incorporate, in a one-pipe steam heating system, air vents on radiators which can be set to vent at different rates in order to provide controlled distribution of steam to the radiators and at the same time to provide in the system 55 a vacuum or negative pressure relief valve so arranged and constructed as to operate at the beginning of each cycle to recharge the system with air at atmospheric pressure so that the adjustable vents on the radiators may be brought into play to deliver their full efficiency on every cycle of operation. We have set forth in detail a preferred means of carrying out our invention, but we wish it distinctly understood that other means capable of the same functions could be used. 60 The present application is to be considered illustrative only and the scope of our invention is to be limited only by the appended claims.

We claim:

1. In a steam heating system for heating enclosed spaces, in combination, a source of steam, a plurality of radiators, pipes for conducting the steam to said radiators, vents on the radiators permitting the steam to reach said radiators at pre-determined times, and means for opening 70
- 75

- said system to the atmosphere, said means comprising a valve opened by actuation of a thermostat under the influence of falling temperature in the space to be heated and closed by the 5 actuation of a second thermostat within said system under the influence of steam generated after said valve is opened.
2. In a steam heating system for heating enclosed spaces, operating in cycles, in combination, a source of steam, radiators having air vents thereon, pipes connecting said source of steam and radiators, and a valve associated therewith, means for setting said source of steam in operation, means to simultaneously open said valve, 10 thereby admitting atmospheric pressure to said system, pressure operated means for opening said air vents when the pressure in the system is substantially atmospheric, thermostatically controlled means for closing said valve and other 15 thermostatic means to close said air vents to seal said system after the generation of steam, means for stopping the generation of steam at a predetermined rising space temperature, and means for thereafter maintaining said valve means and 20 said air vents in closed position when the pressure within the system is less than atmospheric and the space temperature is above a pre-determined point.
3. A heating system for enclosed spaces, 25 comprising radiators with vents thereon, said vents normally open under atmospheric pressure in the system, means for closing said vents when the pressure within said radiators is less than atmospheric, and a valve operable at a predetermined falling space temperature to open said system to the atmosphere thereby reopening said vents.
4. In a steam heating system for heating enclosed spaces and operating in cycles, in combination, means for supplying steam intermittently, a plurality of radiators, means for conducting said steam from said supply means to said radiators, means for maintaining a negative pressure in said system when said steam is not being supplied, valve means operative thereafter at a predetermined falling space temperature for restoring the pressure in said system to atmospheric pressure prior to supplying steam to the radiators on the next cycle, and means for thereafter closing said valve before said steam supply is discontinued.
5. In a steam heating system for heating enclosed spaces, a vacuum relief valve connecting said system with the atmosphere, a thermostat 55 in one of said spaces actuated by a falling space temperature to actuate means to open said valve and a second thermostat within said system actuated by steam generated thereafter to close said valve.
6. In a steam heating system for heating enclosed spaces and operating in cycles, in combination, a steam source, radiators with air vents,
- pipes therebetween, and a valve mounted thereon, means controlled by the falling temperature of one of said spaces to actuate said steam source to start a cycle and to positively open said valve thereby admitting atmospheric pressure to said system prior to delivery of steam to said radiators, means operative thereafter to close said valve, and thermostatic means to close said air vents, means controlled by the rising temperature of one of said spaces to discontinue said steam supply, and means for maintaining said system sealed against a negative pressure of any degree created in said system by condensation of said steam as long as said space temperature remains above a predetermined point.
7. A method of heating by steam in which each cycle comprises the following steps, setting a source of steam in operation, transmitting steam to radiators and at the same time driving air from said radiators to the atmosphere, then sealing the entire system, said sealing to be completed before or about the time the supply of steam is discontinued, discontinuing the supply of steam, then allowing the steam to condense to create a negative pressure in the system, then opening the system to the atmosphere while simultaneously setting the source of steam in operation to commence the next cycle.
8. In a steam heating system for heating enclosed spaces, in combination, automatic means for supplying steam intermittently, a plurality of radiators, pipes for conducting the steam to said radiators, vents on the radiators permitting the steam to reach said radiators at predetermined times, and means for opening said system to the atmosphere at or before the commencing of said supply of steam, said means comprising a valve opened by actuation of a thermostat under the influence of falling temperature in the space to be heated and other means for closing said valve thereafter before the cessation of the supply of steam.
9. In a steam heating system in which steam is supplied intermittently, a source of steam, a vacuum relief valve connecting said system with the atmosphere, means for opening said valve at the same time said source of steam is set in operation, and means for closing said valve before the steam is discontinued.
10. A method of heating by steam in which each cycle comprises the following steps, setting a source of steam in operation, filling radiators with steam, sealing the system, discontinuing the supply of steam, then allowing the steam to condense to create a negative pressure, then restoring the pressure in said system to atmospheric immediately after setting said source of steam in operation.
